REAR VIEW MIRROR

William R. Snell, 4145 Bluestone Road, Cleveland, Ohio

Filed Nov. 1, 1961, Ser. No. 67,343

Term of patent 14 years

(Cl. D14—6)

FIG. 2

FIG. 1

FIG. 3

FIG. 4

FIGURE 1 is a front elevation of a rear view mirror showing my new design;

FIGURE 2 is a top plan view thereof;

FIGURE 3 is a rear elevational view thereof; and

FIGURE 4 is an end elevational view taken from the left of FIGURE 1.

I claim:

The ornamental design for a rear view mirror, as shown.
